CLAIM

The ornamental design for a windshield wiper, as shown and described.

DESCRIPTION

FIG. 1 is a perspective view of a windshield wiper, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a demonstration of the secondary case covering the piece of the windshield wiper;

FIG. 9 is a demonstration of the assembling of the windshield wiper;

FIG. 10 is a demonstration of the main case of the windshield wiper

FIG. 11 is a demonstration of the main case of the windshield wiper with an alternate connector; and,

FIG. 12 is a demonstration of the main case of the windshield wiper with another alternate connector.

In the drawings, the broken lines in FIGS. 11 and 12 depict portions of the article that form no part of the claim.
